MACHINE FOR REPOSITIONING CARTRIDGE
AND LINK BELTSElmer Lovell Smith, Longmeadow, and Carlton
Wetsel, Springfield, Mass., assignors to Package
Machinery Company, Springfield, Mass., a cor-
poration of Massachusetts

Application October 6, 1944, Serial No. 557,504

6 Claims. (Cl. 86—48)

1

This invention relates to a machine for repositioning and verifying the position of cartridges in link belt ammunition and has for its object the provision of a small light portable machine of easily running character suitable to either hand or power operation.

In link belt ammunition the cartridges often become loose or misaligned in the connecting links and it is therefore desirable to run such link belts through a repositioning machine for accurate verification prior to the use of such ammunition in automatic firearms.

The particular features of improvement herein have to do with the means for mounting the loading plungers, and the driving means therefor, all to the end of making a machine especially easy for operation by hand.

In the drawings:

Fig. 1 is a perspective view of the machine with the infeed cover in lifted position to show the feed wheel thereof;

Fig. 2 is a side elevation of said machine from the infeed side;

Fig. 3 is a front end elevation of the machine; and

Fig. 4 is a sectional view taken along the line 4—4 of Fig. 3 looking in the direction of the arrows.

Referring to said drawings the main frame of the machine is indicated at 1 and said frame is provided at the front and rear ends thereof with handles such as 2, whereby the same may be manually carried about. In feed chute 3 is provided at one side of the machine for guiding therein the link-belt ammunition comprising cartridges C and connecting links L. A drum shaft 4 is mounted in suitable bearings for rotation in the frame of the machine and carries splined near its forward end an abutment sprocket wheel 5 adapted for lengthwise adjustment thereon and secured in position by spanner nuts 6 and 6a one at each side of said sprocket 5 as shown in Fig. 4. Also splined on the shaft 4 for rotation therewith is a drum-like feed wheel 7 fastened in position against a shoulder by spanner nut 7a and provided on its periphery with pockets or recesses 8 in which the cartridges of the link belt are adapted to mesh for being fed through the machine. In the travel of the link belt through the machine, the links L do not mesh with the feed wheel but are guided between the side of the pockets 8 and the abutment sprocket 5. The rear face of this sprocket 5 serves as an end abutment for holding said links to an accurate position

2

when the cartridges are pushed therethrough by the positioning means as hereinafter described.

At the rear of feed wheel 7 and also carried on said shaft 4 for rotation therewith, is a plunger ring 9 which has fastened to its periphery, a ring gear 10 formed with a spur gear face, 11 and a beveled gear face 12. Mounted in circular equi-spaced disposition around the plunger ring 9 are a series of independently slidable plungers 13, the forward ends of which are adapted to be brought into successive alignment with the bases B of said cartridges C as the latter are carried over the top of the feed wheel in pockets 8. The front portions of the plungers are recessed or hollowed out to avoid any contact with the primers of the cartridge and the front end 14 of each plunger is adapted for engagement with a return cam later described.

The rear part of the main frame is provided with a housing extension 1a within which is mounted the driving mechanism for the plungers 13. A fixed axle bearing 15 is mounted in the housing 1a in a position at right angles to the shaft 4. Rotatably mounted on said axle bearing 15 is a lantern pinion 16 disposed in tangential relation to the plunger ring and more particularly to the rear ends of the circular series of plungers 13 in the face of said plunger ring 9. In other words the lantern pinion rotates in face wheel relationship to said plunger ring. Each of the trundle bars 17 of said lantern pinion carries a rotatable sleeve 18 which has a limited sliding movement on its bar 17 to serve as a non-friction roller for engaging the rear of head 14 of a plunger 13 as shown in Fig. 4.

The pitch or circular distance between trundle bars is the same as that for the plungers 13 and it will be understood that the rotation of said lantern pinion will bring its trundles 17, 18 into successive engagement with the rear ends of plungers 13 within the plunger ring 9 for imparting thereto a forward movement against the bases of the cartridges. The connecting links L for the cartridges are held against the sprocket 5 as a limiting abutment whereby the cartridges are thrust home into properly positioned alignment within the links.

The lantern pinion 16 has fixed thereto a beveled gear 20 in driving mesh with the beveled face 12 of the ring gear 10. The main driving shaft 21 for the machine is mounted in the main frame 1 in parallel relation to shaft 4 and at its rear end has pinion 22 meshing with the spur face 11 on the said ring gear 10. A crank handle 23 is fixed to shaft 21 and the operation of the main shaft

thus drives the feed wheel shaft which in turn drives the lantern pinion. The return movement of said plungers 13 is effected by a profile cam wall 24 fixed to the lower part of frame 1, which engages the forward ends 14 of said plungers as the latter are carried around by the continued rotation of said plunger ring (see Fig. 4).

In the mechanism described, return springs for the plungers are not employed. Thus there is no resistance load to be overcome in the operation of the machine except the necessary work of re-positioning the cartridges. The frictional resistance of the moving parts is negligible and the maximum results in easy running character are obtained for this type of machine.

We claim:

1. A machine for pushing cartridges into position in belt ammunition, comprising in combination a rotatable feed wheel for progressively feeding a belt of cartridges, a plunger ring rotatably carried with said feed wheel, a circular series of independently slideable plungers mounted in said ring and positioned for successive alignment with the bases of the cartridges on said feed wheel, a driver for imparting a forward movement successively to the several plungers in said ring, comprising a lantern pinion mounted for rotation in face wheel relationship to said plunger ring so that a rotation of said lantern pinion serves to bring its trundles into engagement successively with the rear ends of said several plungers.

2. A machine for pushing cartridges into position in belt ammunition, comprising in combination a rotatable feed wheel for progressively feeding a belt of cartridges, a plunger ring rotatably carried with said feed wheel, a circular series of independently slideable plungers mounted in said ring and positioned for successive alignment with the bases of the cartridges on said feed wheel, a driver for imparting a forward movement successively to the several plungers in said ring, comprising a lantern pinion mounted for rotation in face wheel relationship to said plunger ring so that a rotation of said lantern pinion serves to bring its trundles into engagement successively with the rear ends of said several plungers, and a stationary cam to return said plungers during the continued rotation of said plunger ring.

3. A machine for pushing cartridges into position in belt ammunition, comprising in combination a rotatable feed wheel for progressively feeding a belt of cartridges, a plunger ring rotatably carried with said feed wheel, a circular series of independently slideable plungers mounted in said ring and positioned for successive alignment with the bases of the cartridges on said feed wheel, a driver for imparting a forward movement successively to the several plungers in said ring, comprising a lantern pinion mounted for rotation in face wheel relationship to said plunger ring so that a rotation of said lantern pinion serves to bring its trundles into engagement successively with the rear ends of said several plungers, a drive shaft for operating said feed wheel and plunger ring, and a bevel gear connection between said plunger ring and said lantern pinion.

4. A machine for pushing cartridges into posi-

tion in belt ammunition, comprising in combination a rotatable feed wheel for progressively feeding a belt of cartridges, a plunger ring rotatably carried with said feed wheel at one end thereof, 5 a link abutment member rotatably carried with said feed wheel at the other end thereof, a circular series of independently slideable plungers mounted in said ring and positioned for successive alignment with the bases of the cartridges 10 on said feed wheel, a driver for imparting a forward movement successively to the several plungers in said ring, comprising a lantern pinion mounted for rotation in face wheel relationship to said plunger ring so that a rotation of said lantern pinion serves to bring its trundles into engagement successively with the rear ends of said several plungers.

5. A machine for pushing cartridges into position in belt ammunition, comprising in combination a rotatable feed wheel for progressively feeding 20 a belt of cartridges, a plunger ring rotatably carried with said feed wheel, a circular series of independently slideable plungers mounted in said ring and positioned for successive alignment with the bases of the cartridges on said feed wheel, a driver for imparting a forward movement successively to the several plungers in said ring, comprising a lantern pinion mounted for rotation in face wheel relationship to said plunger ring, with the axis of rotation of said lantern wheel at right angles to the axis of rotation of said plunger ring so that a rotation of said lantern pinion serves to bring its trundles into engagement successively with the rear ends 25 of said several plungers.

6. A machine for pushing cartridges into position in belt ammunition, comprising in combination a rotatable feed wheel for progressively feeding a belt of cartridges, a plunger ring rotatably carried with said feed wheel, a circular series 30 of independently slideable plungers mounted in said ring and positioned for successive alignment with the bases of the cartridges on said feed wheel, a driver for imparting a forward movement successively to the several plungers in said ring, comprising a lantern pinion mounted for rotation in face wheel relationship to said plunger ring so that a rotation of said lantern pinion serves to bring its trundles into engagement successively with the rear ends of said several plungers, the trundles of said lantern pinion each comprising a roller capable of slideable movement 35 lengthwise of the axis.
